(57) **CLAIM**

The ornamental design for a flush-mounted door stop device, as shown and described.

DESCRIPTION

FIG. 1 is an upper perspective view of the retractable, flush-mounted door stop device in a retracted configuration; FIG. 2 is a front side view in elevation thereof; FIG. 3 is a right side view in elevation thereof; FIG. 4 is a rear side view in elevation thereof; FIG. 5 is a left side view in elevation thereof; FIG. 6 is a cross-sectional right side view in elevation thereof;

FIG. 7 is a top view thereof;

FIG. 8 is a bottom view thereof;

FIG. 9 is an upper perspective view of the retractable, flush-mounted door stop device in an extended configuration;

FIG. 10 is a front side view in elevation thereof;

FIG. 11 is a right side view in elevation thereof;

FIG. 12 is a rear side view in elevation thereof;

FIG. 13 is a left side view in elevation thereof;

FIG. 14 is a cross-sectional right side view in elevation thereof;

FIG. 15 is a top view thereof; and,

FIG. 16 is a bottom view thereof.

1 Claim, 6 Drawing Sheets
